UNITED STATES PATENT OFFICE.

WILLIAM FRANCIS GEDDES, OF SUBIACO, WESTERN AUSTRALIA, AUSTRALIA, AS-
SIGNOR OF THREE-EIGHTHS TO WALTER SCHOFIELD, OF BASSENDEAN, WESTERN
AUSTRALIA.

INTERNAL-COMBUSTION ENGINE.

Application filed October 23, 1924. Serial No. 745,350.

To all whom it may concern:

Be it known that I, WILLIAM FRANCIS GEDDES, a subject of the King of Great Britain and Ireland, and resident of Subiaco, in the State of Western Australia, Commonwealth of Australia, have invented an Improvement in Internal-Combustion Engines, of which the following description, in connection with the accompanying drawing, is 10 a specification, like characters on the drawing representing like parts.

This invention relates to improvements concerning internal combustion engines.

In internal combustion engines, as hitherto constructed, connecting rods have been connected to cranks operating a crank shaft. Therefore, with a uniform speed of crank shaft, each stroke of the piston has had the same velocity. It is considered that the 20 comparatively low efficiency of the internal combustion engine is largely due to too rapid piston velocity during the power stroke, which precludes adequate absorption of the explosive effort.

25 The varying torque due to the changing positions of the connecting rods and cranks also reduces the efficiency.

The present invention discloses means whereby the explosion and intake piston strokes can be of comparatively slow speed, whilst the scavenging and compression strokes will be of higher speed.

To enable the invention to be more readily understood reference will now be made 35 to the accompanying drawings, in which:—

Fig. 1 is a side elevation partly sectional of a unit constructed according to the invention.

Fig. 2 is a diagrammatic representation to 40 indicate positions of the crank and connecting rod at various parts of the up and down strokes.

Referring more specifically to Fig. 1, the piston 10 can have a gudgeon pin 11 of the 45 conventional form. A connecting rod 12 at the big end is pivoted and fulcrumed to a lug 13 of a rocking and slotted inclined bent lever 14. This lever is inclined upwardly so as to be at an angle of 45° when the piston 50 is at the top of the stroke and to be approximately horizontal when the piston is at the bottom of the stroke. Such lever extends laterally and is fulcrumed at 15. The crank shaft 16 is approximately in horizon-

tal alignment with the fulcrum 15 when the 55 invention is applied to a vertical engine. Said crank shaft has a crank 17 supporting a crank pin 18, that is embraced by a shrouded roller 19 running in the slot of the lever 14. Alternatively, a sliding block 60 could be used.

Reciprocation of the connecting rod 12 results in the slotted lever 14 being rocked and in the roller 19 being rolled backwards and forwards in the slot thereof. Meanwhile the crank pin 18 is being rotated in the path of the dotted line shown in Fig. 1, whereby the crank shaft 16 carrying the fly wheel is also rotated. Relative movement between the piston and the crank shaft does 70 not have the simple relationship that it does in the conventional mechanism. This statement will be explained by reference to the diagrammatic representation shown in Fig. 2. In this *a*, *a'* represent respectively the 75 centres of the gudgeon pin and the crank pin when the piston is at the starting point for the downward stroke; *b*, *b'* represent the aforesaid centres when the piston has travelled half of its downward stroke; *c*, *c'* 80 represent the aforesaid centres when the piston is at the end of the downward stroke; *d*, *d'* represent the aforesaid centres when the piston has travelled half of the return stroke. This means that whilst the gudgeon 85 pin and attached piston have travelled from *a* to *c*, the crank pin has travelled from *a'* to *c'*, or about $\frac{5}{8}$ of a revolution. Whilst the gudgeon pin and piston are travelling the return stroke from *c* to *a*, the crank pin 90 will travel from *c'* to *a'*, or about $\frac{3}{8}$ of a revolution.

Translated into terms of practice where there is a comparatively constant speed at the crank shaft the foregoing means that 95 each piston stroke is relatively of slow speed, whilst the return stroke is correspondingly faster.

The invention as applied to a four cycle engine results in the explosion and intake 100 strokes, being comparatively slow, whilst the scavenging and compression strokes are correspondingly faster. It should be noted that the lever 14 is fulcrumed laterally to the left side of the cylinder to obtain the effect peculiar to my invention when the crank rotates in a clockwise direction. Should it 105 be necessary to apply my invention to an

engine in which the crank normally rotates in an anti-clockwise direction, then the lever 14 will be fulcrumed laterally to the right of the cylinder.

It should further be noted that should the engine be inverted as compared to the position which is conventional, the following relative positions will be necessary. The power stroke will move upwardly, whilst the 10 bent lever 14 will be inclined downwardly and will be fulcrumed to the right of the cylinder to obtain the results accruing from this invention when the crank is rotating in a clockwise direction. Usually it will be 15 preferable to have a plurality of units operating the same crank shaft. The units will be positioned in such relative stroke positions as are adapted to give a well balanced power plant.

20 I claim:—

1. In an internal combustion engine, the combination of a cylinder, a piston working therein, a connecting rod, a slotted rocking lever fulcrumed laterally left of the cylinder and pivoted to the connecting rod, and a crank slidingly connected to the slotted lever and rotated in a clockwise direction thereby.

2. In an internal combustion engine, the 25 combination of a cylinder, a piston working therein, a connecting rod, a slotted upward-

ly inclined and bent rocking lever fulcrumed laterally left of the cylinder and pivoted to the connecting rod, and a crank slidingly connected to the slotted lever and rotated 35 in a clockwise direction thereby.

3. In an internal combustion engine, the combination of a slotted upwardly inclined and bent lever fulcrumed on the left side, a crank slidingly connected to the slotted lever 40 and rotated in a clockwise direction thereby, and a crank shaft approximately in horizontal alignment with the fulcrum of the inclined lever.

4. In an internal combustion engine, the 45 combination with a cylinder, of a piston working therein, a connecting rod, a crank shaft having a crank and a slotted rocking lever fulcrumed laterally of the cylinder at such a point that a line drawn through the 50 fulcrum and the crank shaft is approximately perpendicular to the cylinder axis, the slotted portion of said lever receiving the crank and being inclined relative to the cylinder axis, the fulcrum point and inclination of the lever being such that during the power stroke and suction stroke the crank will be turned through a greater arc 55 than during the compression stroke and scavenging stroke.

Dated this 18th day of September, 1924.

WILLIAM FRANCIS GEDDES.
